UNITED STATES PATENT OFFICE.

MARTIN V. SHAFF, OF LOS ANGELES, CALIFORNIA.

DESIGN FOR A DISPLAY-RACK.

SPECIFICATION forming part of Design No. 28,263, dated February 8, 1898.

Application filed May 3, 1897. Serial No. 634,971. Term of patent 7 years.

To all whom it may concern:

Be it known that I, MARTIN V. SHAFF, a citizen of the United States, residing in the city of Los Angeles, in the county of Los Angeles and State of California, have invented and produced an original Design for a Display-Rack, of which the following is a specification, reference being had to the accompanying sheet of drawings, forming part thereof.

- The figure on the annexed drawing is a general perspective view of my new and original design for a display-rack consisting of the lower frame A, having the parallel standards A' attached at the center portion. The lower

member A has end cross-pieces B for steady- 15
ing the said rack in its upright position. The upper member consists of two slides C and a cross-bar D, to which hooks E are fastened at the ends whereto the background is suspended. 20

What I claim is as follows:

The design for a display-rack or background-supporter as herein shown and described.

MARTIN V. SHAFF.
